UNITED STATES PATENT OFFICE

GEORGE A. SIMONS AND GEORGE FREEBERG, OF MINNEAPOLIS, MINNESOTA, ASSIGNEES
TO SIMONS MILLWORK, INC., OF MINNEAPOLIS, MINNESOTA, A CORPORATION OF
MINNESOTA

DESIGN FOR A STAIRWAY UNIT

Application filed June 15, 1929. Serial No. 31,723. Term of patent 14 years.

To all whom it may concern:

Be it known that we, GEORGE A. SIMONS and GEORGE FREEBERG, citizens of the United States, residing at Minneapolis, county of Hennepin, and State of Minnesota, have invented a new, original, and ornamental Design for Stairway Unit, of which the following is a specification, reference being had to the accompanying drawing, forming part thereof.

Figure 1 is a side elevation view of the stairway unit showing our new design.

Figure 2 is a front perspective view of a portion of the same.

We claim:

The ornamental design for a stairway unit as shown.

GEORGE A. SIMONS.
GEORGE FREEBERG.
